UNITED STATES PATENT OFFICE.

LEONARD DE WIT, OF CHICAGO, ILLINOIS.

DESIGN FOR A HEATER CASING OR SIMILAR ARTICLE.

Application filed May 13, 1926. Serial No. 17,682. Term of patent 14 years.

To all whom it may concern:

Be it known that I, LEONARD DE WIT, a citizen of the United States, and resident of Chicago, county of Cook, and State of Illinois, have invented a new, original, and ornamental Design for Heater Casing or Similar Article, of which the following is a specification, reference being had to the ac-

companying drawing, forming a part thereof, wherein—

Fig. 1 is a perspective view of an oven embodying the design.

I claim:

The ornamental design for a heater casing or similar article as shown.

LEONARD DE WIT.
